UNITED STATES PATENT OFFICE

132,432

DESIGN FOR A COMBINED LATHE AND STOCK SUPPORT

William K. Millholland, Indianapolis, Ind.

Application August 14, 1941, Serial No. 102,841

Term of patent 14 years

To all whom it may concern:

Be it known that I, William K. Millholland, a citizen of the United States, residing at Indianapolis, in the county of Marion and State of Indiana, have invented a new original, and ornamental Design for Combined Lathe and Stock Support, of which the following is a specification, reference being had to the accompanying drawings, forming a part thereof.

Fig. 1 is a perspective view taken from the front and tail-stock end of a combined lathe and stock support embodying my design;

Fig. 2 is a perspective view taken from the rear and tail-stock end thereof; and

Fig. 3 is a perspective view taken from the front and head-stock end thereof.

Fig. 4 is a perspective view taken from the rear and head-stock end thereof.

I claim:

The ornamental design for a combined lathe and stock-support, as shown.

WILLIAM K. MILLHOLLAND.
